WALTER B. PEDELTY, OF MASON CITY, IOWA.

CENTRIFUGAL FAN.

Application filed October 20, 1926. Serial No. 142,842.

This invention relates to improvements in centrifugal fans with particular reference to fans of the type commonly used for wind stackers for threshing machines, corn huskers, etc.

The objects of this invention are to provide an improved fan structure in which each of the wings or blades will have walls which converge from the inner to the outer end of the wing and re-inforce each other;—to provide such a fan wing structure with a filler between the walls which will prevent vibration and consequent crystallization and will also prevent the development of eddy currents and cross currents between the walls of the blade or wing when in rotation;—to provide improved connecting means whereby the wings may be secured to the shaft;—to provide a fan structure in which the fan may be operated with two diametrically opposed wings revolving at slow speed with a capacity for delivering a greater quantity of material (air and straw or other material of a similar nature) than can be delivered by fans in common use having a greater number of wings operative in a casing of the same diameter and under like conditions;—and in general to provide a fan of increased capacity and durability and of greater efficiency in avoiding winding tendencies or clogging when handling wet or congested masses of fibrous material.

In drawings:

Figure 1 is a side elevation of a fan embodying my invention.

Figure 2 is a similar view with a side wall of the casing removed to expose the fan blades or wings.

Figure 3 is a detail view of the wings associated with a connected fragment of the shaft.

Figure 4 is an edge view of the wing structure shown in Fig. 3.

Figure 5 is a view similar to Figure 4, but showing a slight modification.

Like parts are identified by the same reference characters throughout the several views.

The fan casing 10 is similar to those in ordinary use for like purposes and is provided with an ordinary tangentially extending outlet tube 11. But the inlet opening 12 is formed in the side wall of the casing and has the form of a major segment of a circle.

which includes the projected axis of the shaft, the opening having a straight marginal wall 13 in a chord of said circle, which is pitched obliquely in the general direction of the outlet. This opening allows material to enter the fan casing in the path of the fan wings at a point where it will be struck by the wings or blades and batted or caused to rebound through the chute or passage 11. The fan wings are two in number and as shown in Figures 1 to 5 they are formed of a pair of elongated plates 15 and 16 having their central portions bolted to opposite sides of a square shaft 17, several bolts 18 being preferably employed. These plates 15 and 16 have substantially true plane surfaces and are made to converge progressively toward their respective ends, thereby forming a pair of wedge shaped or tapering wings with outer margins substantially parallel with the shaft axis and the outer marginal portions being secured together in any suitable manner as indicated by the row of rivets 19 in Figure 3. The plates may, of course, be welded, or if desired, the rivet heads may be counter-sunk to present a smooth surface for contact with the material.

Wedge shaped filler blocks 20 are interposed between the plates in each wing. The inner ends of these filled blocks preferably abut the shaft and their outer ends may extend as far as is conveniently practical toward the extremities of the wings between the converging walls, i. e. between plates 15 and 16. Suitable rivets 21 connect the plates and filler blocks at intervals, and the filler blocks not only re-inforce the plates but prevent them from vibrating or from buckling under stresses imposed by impact against any hard material such as stones, sticks or pieces of metal contained in the straw that is being delivered through the chute.

Only two wings are provided and by employing plates of sufficient length to span the shaft and form the wings at the respective sides thereof it becomes possible to provide a wing structure of great strength which can be secured to the shaft without difficulty and which presents an unbroken surface from the tip of one wing to the tip of the opposing wing.

A wing structure of this type can be manufactured at a minimum expense and

each wing virtually constitutes a truss which cannot be broken or distorted by any ordinary stress or impact.

The working face of each wing is oblique 6 to a radial plane through the shaft and the tip of the wing, the pitch being in a direction opposite that of rotation and I have discovered that a blade so constructed will deliver straw without winding and without 10 tangling or breaking it. It will also deliver the straw through a chute in such a manner as to cause it to float outwardly from the mouth of the chute and lie flat on the stack, whereas ordinary centrifugal fans used as 15 wind stackers, not only break and tangle the straw, but deliver large portions thereof on end in such a manner as to direct rain water into the stack instead of facilitating the building of a stack which will shed water. 20 The admission of the material to the fan casting at a point where it will be immediately struck by one of the wings and thrown through the chute is an important factor contributing to this result. 25 I also find that a two wing fan having a diameter of 46 inches from the tip of one wing to the tip of the other will be at least equally effective for the delivery of fibrous material through the chute as a four wing 30 fan of ordinary construction having the same diameter and which requires substantially twice the speed of rotation in order to approximate the capacity of my improved fan. More specifically, it may be stated 35 that ordinary fans employed for wind stackers in connection with threshing machines are four wing fans and require a speed of approximately 900 R. P. M. whereas my improved fan has but two wings 40 and requires for the same duty a speed of only about 430 R. P. M.

Referring to Figure 5 it will be observed that the structure is the same as that disclosed in the other views with the exception 45 that the portion 25 of the shaft which is secured to the fan is cylindrical and is connected by a key 26 with a block 27 which fills the central portion of the space between the two plates 15 and 16 and to which the 50 plates are secured by sets of bolts or rivets 28 which pass through the block on opposite sides of the shaft. In this structure, the block may be of an elongated rectangular form and the filler blocks 20 will, of course, 55 be correspondingly shortened in proportion to the additional space occupied by the connecting block 27. The convergence of the wing plates is wholly due to the pitch of the plate which forms the working face, this feature being of course also available for use 60 in the fan structure as shown in Figures 1 to 4.

I claim:

1. In a centrifugal fan for delivering

straw and other solid materials in an air 65 blast, the combination with a shaft, of a pair of opposed wedge shaped wings, each having substantially true plane surfaces which converge from the vicinity of the shaft to the outer margin of the wing. 70

2. In a centrifugal fan for delivering straw and other solid materials in an air blast, the combination of a shaft and a single pair of oppositely extending wings, each composed of metal plates spaced apart 75 adjacent to the shaft and converging in the direction of their outer end margins, said plates having flat, substantially true plane surfaces and being secured together for mutual reinforcement. 80

3. In a centrifugal fan for delivering straw and other solid materials in an air blast, the combination of a shaft and a single pair of oppositely extending wings, each composed of metal plates spaced apart adjacent to the shaft and converging in the direction of their outer end margins and forming true wedge shaped structures with said margins substantially parallel to the shaft, said plates being secured together for mutual reinforcement, and the space between them being provided with a filler block conforming to and filling the space which it occupies between the plates and secured to the plates. 90

4. In a centrifugal fan for delivering straw and other solid materials in an air blast, the combination of a shaft and a pair of oppositely extending wings, each composed of flat metal plates spaced apart adjacent to the shaft and converging in the direction of their outer end margins, said plates being secured together for mutual reinforcement, and the space between them being substantially filled with non-metallic material in re-inforcing relation to the plates and of substantially uniform thickness throughout each transverse dimension. 100

5. In a centrifugal fan for delivering straw and other solid materials in an air blast, the combination with a shaft having a rectangular wing supporting portion non-rotatable with reference to the shaft, of a single pair of elongated flat metallic wing plates having their central portions respectively secured to opposite side faces of said rectangular wing supporting portion and end portions converging on opposite sides of the shaft toward a line parallel with the shaft and secured together to form generally wedge shaped wings. 110

6. In a centrifugal fan for delivering straw and other solid materials in an air blast, the combination with a shaft having a rectangular wing supporting portion non-rotatable with reference to the shaft, of a pair of elongated metallic wing plates having their central portions respectively se- 120

- cured to opposite side faces of said supporting portion, and end portions converging on opposite sides of the shaft toward a line substantially parallel with the shaft 5 and secured together to form generally wedge shaped wings, and a body of non-metallic filling material between the plates secured to the plates and adapted to reinforce them.
- 10 7. In a centrifugal fan for delivering straw and other solid materials in an air blast, the combination with a shaft of a pair of generally wedge shaped wings rigidly secured thereto, each of said wings having 15 flat metallic surfaces in planes normal to the plane of rotation, converging to an outer edge margin, and a non-metallic intervening filler portion.
8. A centrifugal fan rotor comprising the combination of a pair of rectangular plates 20 having their central portions in spaced relation to each other and their end portions convergent and secured together along lines substantially parallel to the axis of rotation, a driving and spacing member secured to 25 the central portions of the plates, and wooden filler blocks conforming to the spaces between the plates on each side of said driving and spacing member and secured to the plates. 30
